(57) **CLAIM**

We claim the ornamental design for an accessory for hair styling and hair care apparatus, as shown and described.

DESCRIPTION

FIG. 1 is a rear perspective view of an accessory for hair styling and hair care apparatus showing our new design; FIG. 2 is a bottom perspective view thereof; FIG. 3 is a front perspective view thereof; FIG. 4 is a side view thereof; FIG. 5 is a top view thereof; FIG. 6 is a bottom view thereof; and, FIG. 7 is a front view thereof.

The areas within the dashed lines in FIG. 2 and FIG. 6 form no part of the claimed design.

The view opposite the side view of FIG. 4 is a mirror image thereof, and therefore, is omitted.

The accessory for hair styling and hair care apparatus is illustrated with grayscale shading to indicate contrast.
